UNITED STATES PATENT OFFICE

152,982

DESIGN FOR A MUG

Icem Kelley, San Francisco, Calif.

Application October 22, 1946, Serial No. 134,172

Term of patent 3½ years

(Cl. D36—8)

To all whom it may concern:

Be it known that I, Icem Kelley, a citizen of the United States and a resident of San Francisco, in the county of San Francisco and State of California, have invented a new, original, and ornamental Design for a Mug, of which the following is a specification, reference being had to the accompanying drawing, forming a part thereof.

Figure 1 is a perspective view of a mug, showing my new design.

Figure 2 is a fragmentary vertical sectional view taken substantially on the plane of the line 2—2 of Figure 1;

Figure 3 is a fragmentary vertical sectional view taken substantially on the plane of the line 3—3 of Figure 1.

While but one side of the mug is shown in Figure 1, it is understood that the opposite side is substantially identical.

I claim:

The ornamental design for a mug, as shown and described.

ICEM KELLEY.
